UNITED STATES PATENT OFFICE.

EDDY T. McKAIG, OF WAUKEGAN, ILLINOIS.

ТИЛТИНГ ФРОНТ АКСЛЕЙ ДЛЯ ТЕХНИКИ.

1,308,289.

Specification of Letters Patent.

Patented July 1, 1919.

Application filed April 12, 1918. Serial No. 229,459.

To all whom it may concern:

Be it known that I, EDDY T. McKAIG, a citizen of the United States of America, and a resident of Waukegan, county of Lake, 5 State of Illinois, have invented certain new and useful Improvements in Tilting Front Axles for Vehicles, of which the following is a specification.

This invention relates to front axles for 10 vehicles and particularly for that class of vehicles known as tractors designed for use on farms to draw various kinds of farming machines such as plows, harrows, etc.

These tractors necessarily are obliged to 15 pass over very rough ground and the object of the present invention is to provide a front axle frame which will accommodate itself to these uneven surfaces.

The invention consists in mounting the 20 stub axles between two separated plates secured together and pivoted to the main frame of the tractor by a horizontally disposed pivot.

The invention further consists in the 25 means whereby said stub axles may be simultaneously moved about their pivots to guide the vehicle.

The invention further consists in certain 30 novel features and arrangement of parts which will be more fully understood by reference to the description of the drawings and to the claims to be hereinafter given.

For the purpose of illustrating the invention one preferred form thereof is illustrated in the drawings, this form having been found to give satisfactory and reliable results, although it is to be understood that the various instrumentalities of which the invention consist can be variously arranged 40 and organized and that the invention is not limited to the precise arrangement and organization of these instrumentalities as herein shown and described, except as required by the scope of the appended claims.

45 Of the drawings:

Figure 1 represents a plan of a device embodying the principles of the present invention.

Fig. 2 represents an elevation of the same 50 partly in section, and

Fig. 3 represents a transverse section on line 3, 3 on Fig. 2.

Similar characters designate like parts throughout the several figures of the drawings.

55 In the drawings 10-10 are two sills of a

truck or tractor, the forward ends of which are connected together by means of a transom 11 secured to said sills by the angles 12. To the rear of the transom 11 the sills 10-10 are also connected together by means of a horizontal plate 13 secured to the under sides of said sills. This plate 13 has secured to its lower face a member 14 having depending ears 15 between which is positioned a vertical rocking member 16, said rocking member being pivoted to said ears 15 by means of a pivot pin 17.

Depending from the rear face of the transom 11 is a bracket 18 the lower end of which is positioned between upwardly extending ears 19 formed upon a plate 20 extending transversely of said sills 10-10.

The ears 19 are pivotally connected to the lower end of the bracket 18 by means of a 75 pivot pin 21 in alignment with the pivot pin 17.

The plate 20 is provided with bearings 22 at the opposite ends thereof and has extending laterally therefrom the curved extensions 23 concentric with the bearings 22. Beneath the plate 20 is an under plate 24 similar in outline and separated from the upper plate 20 by means of tubular members 25, through each of which extends a bolt 26, 85 having a nut 27 threaded to the lower end thereof.

The opposite ends of said lower plate 24 are provided with bearings 28 in alignment with the bearings 22 and between said bearings 22 and 28, are positioned the hubs 29, of the stub axles 30 through which hubs extend pivot members 29*, mounted in the bearings 22 and 28.

Each hub 29 of the stub axles 30 has an 95 extension 31 on the end of which is mounted a revoluble truck 32 adapted to travel between the laterally extending curved tracks 23 formed upon the upper and lower plates 20 and 24. Each hub 29 is also provided with a laterally extending arm 33, the outer end of which is provided with a pivot pin 34 extending through the forked ends of a rod 35 connecting said arms 33 so that said stub axles may be moved simultaneously 100 about the pivot members 29.

One of the pins 34 has mounted thereon a member 36 to which is pivoted at 37 one end of the rod 38, the opposite end of which is provided with the forked member 39 110 straddling and pivoted to a member 40 adapted to oscillate about a cylindrical pro-

jection 41 on the outer end of a lever 42 secured to the oscillating shaft 43. This shaft 43 is mounted in a bearing 44 secured to the inner face of one of the sills 10.

5 To the upper end of the shaft 43 is secured a segment 45 of a worm gear, the teeth of which mesh with the worm 46 revolutely mounted in a casing 47 secured to a sill 10 and the transom 11. The casing 47

10 is provided with a cover 48 inclosing the worm 46 and the segment 45. The worm 46 is provided with a shaft 49 extending through the casing 47 and having secured to its outer end the revoluble operating rod 50.

15 By rotating this rod 50 motion is imparted to the segment 45 by means of the worm 46 and the lever 42 is thereby moved about the axis of the shaft 43.

This movement, through the link or rod 20 38, causes the arms 33 and the stub axles 30 to be moved about the axes of their pivots 29^x. During this movement of the axles 30 about the pivots 29^x, the trucks 32 move along the curved track 23 extending laterally 25 from the upper and lower plates 20 and 24. These tracks are separated from each other slightly in excess of the diameter of the trucks 32 which normally bear upon the lower track as shown in Fig. 2.

30 The two plates 20 and 24 with their various connections form a frame for the stub axles 30 which are pivoted to said frame in such a manner that they may be easily moved about their pivots 29^x to guide the 35 truck or tractor by simply rotating the operating rod.

Connected to the lower plate 24 at 51 are brace rods 52, the opposite end of each of 40 which is threaded and extends through an opening in one end of the rocker member 16 and has mounted thereon the adjusting nuts 53 and 54 on opposite sides of said rocker member.

These brace rods 52 give a greater rigidity 45 to the front axle frame and permit the said frame and the rocker member 16 to tilt respectively about the pivot pins 21 and 17 when the truck or tractor is passing over uneven surfaces.

50 This makes a very convenient form of front axle for use in tractors and similar vehicles which in their work are obliged to travel over rough and broken ground.

It is believed that the operation and many 55 advantages of this invention will be fully understood by the foregoing description.

Having thus described my invention, I claim:

1. The combination of a pair of parallel 60 plates having lateral extensions formed integral therewith; a plurality of separators between said plates; a securing bolt extending through each separator and said plates; non-revoluble stub axles having hubs interposed between and pivoted to the ends of

said plates; rollers on the inner ends of said axles adapted to travel between said lateral extensions and limited in their movement in opposite directions by certain of said separators; an arm on each hub; a connector between said arms; and means for moving said stub axles about their pivots. 70

2. The combination of a pivoted frame adapted to be moved in a vertical plane about its pivot and consisting in part of two parallel separated plates having laterally extending curved extensions integral therewith; stub axles having hubs interposed between and pivoted to the opposite ends of said plates and having extensions provided 75 with rollers adapted to travel between said curved extensions; means preventing the displacement of said rollers from said extensions; and means for simultaneously moving said axles about their pivots. 80

3. The combination of a frame consisting in part of two parallel separated plates; stub axles having hubs interposed between said plates and pivoted thereto; means for moving said axles about their pivots; ears 90 on the upper plate; a bracket curved to and extending downwardly from the main frame of the vehicle; a pivoted connection between said ears and bracket; a depending bifurcated bracket on the main frame; a rocker 95 plate pivotally mounted in said bifurcated bracket; and braces between said rocker plate and said axle frame.

4. The combination of a frame consisting in part of two parallel separated plates, 100 stub axles having hubs interposed between said plates and pivoted thereto; means for moving said axles about their pivots; upwardly extending ears on the upper plate; a bracket secured to the main frame of the vehicle the lower end of which is positioned 105 between said ears; a pivoted connection between said ears and bracket; a cross member secured to the main frame; ears depending therefrom; a pivoted rocker plate mounted between said depending ears with its pivot aligned with said pivotal connection; and brace rods secured at one end to the outer ends of said rocker plate and with their opposite ends diverging and secured to said 110 axle frame. 115

5. The combination of a frame consisting in part of two parallel separated plates each having formed thereon two sets of oppositely disposed curved lateral extensions; non-revoluble stub axles having hubs interposed 120 between said plates and pivoted thereto, said hubs having extensions provided with rollers adapted to travel between said curved lateral extensions; means for moving said axles about their pivots; means for limiting the movement of said extensions about their pivot; ears on the upper plate extending upwardly therefrom; a bracket secured to the main frame of the vehicle with its lower 125 130

end between said upwardly extending ears; a pivoted connection between said ears and bracket; a cross member secured to said main frame; ears depending therefrom; a rocker plate mounted between said ears with its pivot alined with said pivotal connection; brace rods secured at one end to said axle frame and having their opposite ends threaded and extending through said rocker

plate; and adjusting nuts on said threaded ends on opposite sides of said rocker plate.

Signed by me at Waukegan, county of Lake, State of Illinois, this 14th day of November 1917.

EDDY T. McKAIG.
